Des. 195,486
Patented June 18, 1963

195,486

AIR NOZZLE

Theodore Penkoff, 1 John St., Massapequa, N.Y.

Filed Feb. 28, 1962, Ser. No. 69,026

Term of patent 14 years

(Cl. D62—2)

Fig. 1.

Fig. 2.

Fig. 3.

Fig. 4.

FIGURE 1 is an elevational view of the air nozzle, showing my new design looking at one face thereof;

FIGURE 2 is a side elevational view of one side of the nozzle, the opposite side which is not disclosed in the drawing, being substantially the same in appearance;

FIGURE 3 is an elevational view, looking at the face opposite that shown in FIGURE 1; and

FIGURE 4 is a top plan view of the nozzle.
The undisclosed bottom is open.

I claim:

The ornamental design for an air nozzle, substantially as shown and described.
